UNITED STATES PATENT OFFICE.

JOHN E. BELL, OF NEW YORK, N. Y.

SUPERHEATER.

1,296,739.

Specification of Letters Patent. Patented Mar. 11, 1919.

Application filed June 2, 1915. Serial No. 31,689.

To all whom it may concern:

Be it known that I, JOHN E. BELL, a citizen of the United States, residing at New York, in the county of New York and State 5 of New York, have invented a new and useful Improvement in Superheaters, of which the following is a full, clear, and exact description, reference being had to the accompanying drawings, forming part of this 10 specification, in which:

Figures 1, 2 and 3 are sectional views of a portion of a furnace embodying one form of my improved superheater; Fig. 3 being taken on the line III—III of Fig. 2, and Fig. 2 15 showing a portion of said Fig. 1 on a larger scale;

Fig. 4 is a view similar to Fig. 1, but showing a modification;

Fig. 5 is a section on the line V—V of 20 Fig. 4;

Figs. 6 and 7 are sectional views showing another form of my invention; and

Figs. 8, 9 and 10 are detail views herein- 25 after more fully described.

My invention has relation to superheaters, and is designed to provide a superheater which is located in one of the side walls or in the roof of a furnace, the superheater to be in whole or in part out of the path of 30 the furnace gases, and the heat absorbed thereby to be in a large part radiant heat. To utilize radiant heat in this way, it is necessary that some portion of the surface or volume of the furnace emit radiant energy in 35 quantity. For this purpose, I may depend on radiations from the fire surface, where solid fuel is used, and also upon radiations from the firebrick walls and roof of the furnace, and in part upon radiations from the 40 combustion of the illuminants or flame in the furnace.

Heat is transmitted from a hot to a cold body which are separated in two ways: first, by the combination of conduction and con- 45 vention in the intervening medium; and second, by radiation or the transfer of heat through a wave motion in the ether. Heat can pass through a vacuum only by radia- 50 tion. The heat that comes from the sun comes in this way. The heat that passes out through a fire-door opening into a furnace against a rush of cold air inward is radiant heat and is in sufficient amount to quickly burn and blister the fireman unless he pro- 55 tects himself. In ordinary boiler work from twenty-five to fifty per cent. of the total

heat absorbed by the boiler is radiant heat, and comes from the surface of the fuel bed; or if there is a sensible flame in the furnace, part of it from the carbon particles constituting the flame. This portion of the heat is absorbed by the heating surface exposed to the furnace. There is also some radiation from the brick work of the setting, but, the amount of heat emitted by a hot body 65 through radiation diminishes rapidly with a falling temperature. In a general way, the radiation is determined by the application of Stefan's law, and is proportional to the fourth power of the absolute temperature. 70 It is consequently obvious that the amount of heat that is transferred by radiation is more or less negligible, except where the temperatures are high.

My invention provides a superheater having 75 many practical advantages, some of which will be hereinafter more particularly pointed out.

Referring first to that form of my invention shown in Figs. 1, 2 and 3, in which I 80 have shown the superheater located in the roof of a furnace, the numeral 2 designates a furnace and 3 the furnace grate. 4 designates superheater tubes, arranged in parallel, and which may be of the ordinary drawn 85 steel manufacture, but which are surrounded by a metal casing 5. This casing preferably consists of a plurality of sections of cast iron. Adjacent tubes 4 are separated from each other by intervening sections 6 90 of firebrick or other refractory material.

Each section of the cast iron casings 5 preferably has a bottom or face portion 5^a of a shape to completely fill the space between the driving firebrick 6. Back of the 95 bottom or face portion, each casing preferably has a reduced neck portion 5^b, which joins it to that part of the casing which immediately surrounds the superheater tube 4. The purpose of this neck is to provide 100 means for controlling the amount of heat which flows by conduction to the superheater tube. The amount of heat absorbed by radiation diminishes as the temperature of the absorbing surface increases, and the 105 temperature of the absorbing surface will be increased as the area of this neck is diminished. Therefore, by reducing the size of the neck a very material reduction can be made in the amount of heat reaching the superheater. The metal in those 110 portions of the casing sections immediately

surrounding the superheater tubes is of sufficient mass to permit the conduction of heat to all sides of the tube and to insure its being taken up by the tube. The casing 5 may be extended to form rings or eyes 7, engaged by hook bolts 8, to form a means of suspending the superheater from a suitable support. In the construction shown in Figs. 1, 2 and 3, the refractories 6 are 10 supported by the casings, and these, in turn, are supported by the hook bolts 8 from the overhead beam 9, the tubes, casings and refractories constituting the entire roof. It is unnecessary to provide a hook bolt 15 for each section of the casing, but they should be used at proper intervals to prevent any warping or bending of the tubes. In fact, one of the important advantages of this method of construction is the preventing of the tubes from getting out of 20 line. The firebricks 6 not only form a part of the furnace roof, but they preferably extend considerably below the face portions 5^a of the casing sections, so that they shroud 25 or protect the superheater to a certain extent from the radiations, and thus afford another means of regulating the intensity of the heat absorption.

In Figs. 4 and 5, the superheater is shown 30 as arranged in the wall 10 of the furnace opposite the checkerwork outlet 11. The superheater is constructed in substantially the same manner as in the preceding figures, but in this case, the support back of the 35 superheater tubes consists of a buck-stay 12, to which the bolts 13, connected to the casing sections, are secured. By locating the superheater directly opposite the checkerwork, the checkerwork is prevented from 40 becoming overheated and the location and arrangement is a very practical and desirable one.

Another form of my invention is illustrated in Figs. 6, 7 and 8, in which I have 45 shown the superheater as located in the side wall of a boiler furnace and boiler of the Stirling type. In this form of my invention the superheater tubes 14 are of U-form and are stiffened against bending or warping 50 by a cast iron casing 15, generally similar to the casing before described, except that one casing is common to at least both branches of one U-tube. Preferably, the casing is made up in separate sections for 55 each U-tube, although it may be in one piece. The area of the casing around and between the tubes is sufficiently great to permit the rear tube to be heated by the conduction of heat in the usual way through 60 the cast iron around it. This feature of my invention, namely, the protection of two or more adjacent tubes against bending or warping by a cast metal casing may also be used to advantage in water tubes.

In Figs. 9 and 10, I have shown another 65 means for regulating the degree of superheat. This device consists of a movable firebrick shutter 16, with refractory portions 17, extending between adjacent tubes, and which can be moved relatively to the 70 tubes, so as to expose them to a greater or less extent to the heat.

The heat absorbed by a superheater located in the usual way is entirely by contact with the gases, and as a consequence, a relatively large amount of surface must be provided, while I expose the superheater directly to the radiations from the furnace. To increase the surface exposed and also to obtain a material that can withstand high 80 temperatures, I surround the ordinary superheater tube with a heavy cast iron casing. The face of the casing 5^a, as shown in Fig. 3, is, in width, for instance, over twice the 85 diameter of the steel tube and since the projected area only is effective in absorbing radiation, the surface exposed is practically double.

The heat absorbed by the face 5^a, of course, raises the temperature of the portion of the 90 casing marked 5, and if there were no loss of heat, this portion would eventually assume a temperature equal to that of the fire and 95 would be melted and burned away. Since, however, iron is a good conductor, the heat absorbed by the face 5^a is carried back through the metal and finds its way out through the superheater tube into the steam. The difference in the temperature between the face 5^a and the superheater tube will depend upon the resistance to the conduction 100 of heat between the two parts. This, in turn, depends inversely on the conductivity of the metal and the area provided for the heat flow. If, therefore, either the conductivity or the area is reduced, the temperature 105 of the face 5^a will be elevated as compared with the temperature of the superheater tube. By increasing or diminishing the amount of metal in the neck 5^b, the temperature 110 of the face 5^a can be made higher or lower at will. As the temperature of the face 5^a increases, the amount of heat that it re-radiates back to the furnace, according to the law of interchanges, increases, and as a consequence, the net amount 115 of heat absorbed by radiation diminishes.

My invention provides a superheater which can be located conveniently in the setting of the furnace. Under ordinary 120 conditions, it reduces the area of the heating surface very materially, and thus effects a great saving in cost. It also, as has been described, permits the use of simple means whereby the superheater can be adjusted at 125 will. This has not heretofore been possible except in special instances, and by the use of complicated and troublesome devices.

The superheater can be located without difficulty in connection with any sort of furnace used in boiler work.

The particular instances which have been 5 illustrated and described are illustrative only, as the location and arrangement of the superheater may be widely varied in different furnaces, without departing from the spirit and scope of my invention as defined 10 in the appended claims.

I claim:

1. A furnace having a superheater located 15 in one of the walls thereof, a heat conducting casing surrounding the superheater and within the walls of the furnace, a portion of the outer face of said casing being exposed to the radiant heat of the furnace, substantially as described.

2. A furnace having a superheater located 20 in one of the walls thereof, a metallic heat conducting casing surrounding the superheater and within the wall of the furnace, a portion of the outer face of said casing being exposed to the radiant heat of the furnace, said casing having a reduced portion 25 between the exposed face and the superheater incased therein to conduct the heat from the exposed face to the superheater, substantially as described.

3. A furnace having a superheater located 30 in the roof thereof, a metallic heat conducting casing surrounding the superheater and within the roof of the furnace, a portion of the outer face of said casing being exposed to the radiant heat of the furnace, said casing having a reduced portion 35 between the exposed face and the superheater incased therein to conduct the heat from the exposed face to the superheater, substantially as described.

4. A furnace having a superheater comprising a series of superheater tubes and a solid metal casing for said tubes, said casing having a body portion, a head portion 45 arranged to be exposed to the radiant heat, and a neck portion connected to the body portion and the head for conducting the heat from the head to the body portion, substantially as described.

5. A furnace having a superheater com-

prising a series of superheater tubes and a sectional metal casing for said tubes, said casing having a body portion, a head portion arranged to be exposed to the radiant heat, and a neck portion connected to the body portion and the head for conducting the heat from the head to the body portion, substantially as described.

6. A furnace having a superheater comprising a series of superheater tubes, metal 60 casing surrounding said tubes and arranged to conduct heat thereto, and refractory dividing members intermediate the casings of the different tubes, and arranged to prevent the major portions of the bodies of the 65 casings from being exposed to the radiant heat of the furnace, substantially as described.

7. A furnace having a superheater comprising a series of superheater tubes, metal 70 casings surrounding said tubes and arranged to conduct heat thereto, refractory dividing members intermediate the casings of the different tubes, and arranged to prevent the major portions of the bodies of the 75 casings from being exposed to the radiant heat of the furnace, means for supporting said casings, said casings being arranged to support the dividing members, and projections on the dividing members arranged to engage 80 the metal casings to support them in position, substantially as described.

8. A metallic superheater casing having a body portion, a head portion, and a reduced neck portion connecting the head to the body 85 portion, substantially as described.

9. A superheater having a plurality of tubes, metallic superheater casing members having openings therethrough through which the tubes of the superheater extend, super- 90 heater supports, and means for connecting some of the casing members to said supports, substantially as described.

In testimony whereof I have hereunto set my hand.

JOHN E. BELL.
